REGINALD JAMES BRAY, OF DUBLIN, IRELAND, ASSIGNOR TO ELLIOTT-FISHER COMPANY, OF HARRISBURG, PENNSYLVANIA, A CORPORATION OF DELAWARE.

RESET-GUARD FOR ADDING-MACHINES.

1,068,309.

Specification of Letters Patent. Patented July 22, 1913.

Application filed July 24, 1909. Serial No. 509,359.

To all whom it may concern:

Be it known that I, REGINALD J. BRAY, a subject of the King of Great Britain, residing at Dublin, Ireland, have invented certain new and useful Improvements in Reset-Guards for Adding-Machines, of which the following is a specification.

This invention relates to a reset guard for adding machines of that type in which a computing device or register includes a series of denominational members adapted to be operated successively by a master means to accumulate values.

The object of the invention is to provide a guard which will prevent the engagement of the master means with the denominational members of the register unless the register mechanism is in proper condition for the accumulation of values.

20. In the accompanying drawings Figure 1 is a perspective view of a register equipped in accordance with my invention, the mechanism of the register being set and a portion of the master wheel being shown about to move into engagement therewith, the guard being in its normal ineffective position. Fig. 2 is a similar view with the mechanism of the register partially reset and the reset guard in position to prevent the engagement of the register by the master means. Fig. 3 is a detail perspective view of a double reset guard. Fig. 4 is a side elevation of the register with parts thereof broken away and other parts in section to more fully disclose the construction, arrangement and mounting of the reset guard, the positions assumed by the parts corresponding to those shown in Fig. 1. Fig. 5 is a view similar to Fig. 4 with the parts positioned as in Fig. 2.

Each part is indicated by its appropriate reference character in the several views.

It may be stated by way of premise that the present invention has been designed as an improvement on what is known as the Elliott-Fisher writing-adder machine of commerce, though obviously it is susceptible of use in connection with any machine of a broadly analogous class. The Elliott-Fisher machine is a combined typewriter and adder in which a master means is moved laterally by the typewriter carriage to engage any one of a series of denominational members or number wheels of a computing device or register and is rotated dif-

ferent distances or through different angles of motion by the several numeral keys of the typewriter for the purpose of accumulating in the register the values represented by the typewritten digits.

For a more complete disclosure of the machine than is deemed necessary for the present purpose, reference is made to Letters Patent of the United States No. 829,971 to Laganke and Smith.

In the accompanying drawings 1 indicates a computing device or register of a well known type and 2 its master wheel or actuator. The wheel 2 is toothed to engage and operate any one of a series of toothed denominational members or number wheels 3 mounted on a normally stationary shaft 4 extending transversely of the register. The wheels 3 are equipped with suitable carrying mechanism, not shown, and preferably mesh with a corresponding series of registering wheels 5 having digits displayed on their peripheries and exposed at a sight opening 6 through which the total amount accumulated on the register is displayed.

By relative lateral movement of the master wheel and register the former is presented in engagement with successive number wheels 3 and is rotated from 1 to 9 increments for the purpose of accumulating from one to nine units of that denomination to which the engaged number wheel is appropriated. As is well understood in the art, it is necessary to reset the register to zero after the desired computation has been effected and in the type of register shown the primary element of the setting mechanism is a setting lever 7 which, when swung to an upright position and returned to the normal position indicated in Figs. 1 and 4, resets the registering wheels to zero and restores the various mechanisms of the register to normal position.

It has been deemed unnecessary to disclose either the complete setting mechanism or the entire mechanism set thereby, since both are old and well known. It may be stated in passing, however, that the resetting of the number wheels is effected by the rotation of the shaft 4 incident to the upward movement of the setting lever 7, while certain other of the parts are restored to normal position by the return of the lever and the reverse rotation of the shaft 4. It will be seen by Figs. 4 and 5 that such ro-

5 tary movement of the shaft 4 both from and back to normal position is effected by the oscillation of the lever 7 in consequence of a pinion 8 fixed to the shaft 4 adjacent to one end thereof and engaging a segmental rack 9 formed on the front end of the lever 7.

10 It may sometimes happen that in the rapid manipulation of the machine the operator may manipulate the lever 7 to reset the register, but inadvertently fail to restore the lever to its completely depressed or normal position. In that event the master wheel may be brought into engagement 15 with the register and an attempt made to operate the latter before the failure of the operator to complete the resetting of the register is discovered.

20 As heretofore stated, the object of my invention is to provide a guard which will prevent the engagement of the register by the master means unless the mechanism of the register is in properly operative condition. To attain this end a pair of guard disks 10 are fixed to the shaft 4 just beyond each end of the series of number wheels and having a greater diameter than the body portions of the number wheels 3. The 25 guard disks 10, however, are cut away, as indicated at 11, and in the normal position of the shaft 4 these cut away portions 11 of the disks are disposed at the front of the register and substantially coincide with the curved front edges 12 of the register walls, 30 see Fig. 4. In this normal position of the guard disks they do not protrude into the path of lateral movement of the master wheel 9, but on the contrary, are in inactive positions and permit the master wheel 35 to pass freely into engagement with the wheels 3 of the register, see Figs. 1 and 4. As soon, however, as the setting lever 7 of the register is moved from normal position, the consequent rotation of the shaft 4 rotates the guard disk 10 so as to protrude 40 the latter into the path of the master wheel and thus guard the number wheels, or in other words, prevent the master wheel from moving into engagement with said number 45 wheels until the shaft 4 and guards 10 have been completely restored to normal position by the completion of the setting operation.

50 If desired, the top of the register casing may be equipped with a spring 13 engaged 55 by a lug 14 on the resetting lever 7 during the final portion of the retractile movement of the lever. The purpose of this spring is to sufficiently withdraw the lever 7 to project a substantial portion of the guard disks 60 10 into the path of the master wheel unless the lever is completely depressed and located in its normal position. That is to say, if the lever 7 is moved nearly but not quite to its fully set position, a comparatively small portion of the guard disks will

oppose the movement of the master wheel into engagement with the register, but by providing the spring 13 the lever 7, if released by the operator prematurely, will be forced to assume a position which will insure material interference between the master wheel and a reset guard. 70

75 Before concluding, attention is directed to the fact that in one aspect of my invention it constitutes broadly, means for preventing the engagement of a computing mechanism by its operating means unless the former is in condition for operation, and that, in a more specific aspect, it constitutes a reset guard preventing the engagement of the computing device and its actuating means, after the beginning of the resetting operation and until the parts have all been restored to normal position. It is also obvious that while a double reset guard adapted 80 to guard both ends of a series of denominational members has been shown, a single guarding member constitutes a complete embodiment of the invention in one aspect thereof. It is also obviously immaterial 85 what particular form the operating or operated members assume, or whether the relative movement of such members necessary to bring them into co-operative relation is attained by the movement of the operating member, the operated members, or by the 90 conjoint movement of both, since the denominational translation of these members by each of the recited modes is well known in the art to which this invention appertains, and since the guarding means here 95 shown is not dependent upon any particular character of translation for its effectiveness.

100 In the appended claims I have specified 105 guarding means arranged to prevent the engagement of the computing and operating mechanisms except when the computing mechanism is in condition for operation. This language is to be construed broadly 110 since I am the first to provide a guard for preventing the engagement of the computing and operating mechanisms when the computing mechanism is not in condition for operation, regardless of how such condition 115 is brought about. Furthermore, I have specified a setting mechanism which, unless specifically modified in the claims, should be understood to be the mechanism for setting 120 in normal operative position any part of the computing device which must be so set in order to insure its operative condition. While the setting mechanism, indicated in the accompanying drawings, is well known 125 in the art as a means for restoring the number wheels to zero and also for restoring the carrying devices to normal operative position, my invention is believed to be of sufficient breadth to comprehend the use of a guard for preventing engagement of the 130

computing device and its operating means whenever a setting mechanism is out of normal position, regardless of the particular elements of the computing device for the 5 positioning of which the setting mechanism may be employed.

It is thought that from the foregoing, the construction and operation of the described mechanism will be fully understood, but I 10 wish to be distinctly understood as reserving the right to effect such variations of the illustrated structure as may come fairly within the scope of the protection prayed.

What I claim is:—

15. 1. The combination with a computing mechanism and operating mechanism therefor, said mechanisms having relative movement to effect their engagement and disengagement and guarding means operative 20 to prevent the engagement of said mechanisms when the elements of the computing mechanism are out of operative position and to permit the engagement of said mechanisms when the computing mechanism is in 25 condition for operation.

2. The combination with computing mechanism and operating mechanism therefor, relatively movable into and out of co-operative relation, of guarding means movable to 30 permit or prevent the establishment of a co-operative relation between said mechanisms.

3. The combination with computing mechanism and operating mechanism therefor, said mechanisms being relatively movable 35 into and out of engagement, of a movable guard movable into and out of position to prevent the engagement of said mechanisms, and means for moving the guard.

4. The combination with a computing device 40 including setting mechanism, of operating mechanism for the computing device, and a guard operated by the setting mechanism of the computing device and serving in one position thereof to prevent 45 the engagement of the computing device by its operating mechanism.

5. A computing device including a series 50 of toothed wheels, operating mechanism including a toothed master wheel, the series of toothed wheels and the master wheel having relative lateral movement to effect 55 their engagement and disengagement, and a guard movable into and out of position to prevent the engagement of the toothed wheels by the master wheel.

6. The combination with a computing device including a series of toothed denominational members and setting mechanism therefor, of a master actuator adapted to 60 engage and operate the denominational members, and means co-operatively related to the setting mechanism to prevent the operation of the denominational members by the master means when said setting 65 mechanism is out of normal position.

7. The combination with a computing device and operating means therefor, of a movable guard controlling the engagement between the computing device and its operating means, and a spring tending to keep 70 the guard in operative position.

8. The combination with a computing device and its operating means, of a guard controlling the engagement of the computing device by said means, said computing device including setting mechanism controlling the position of the guard, and a spring tending to urge the guard to its active position and arranged to be overcome by the setting mechanism. 75

9. The combination with a computing device and its operating means, of a guard controlling the engagement of the computing device by said means, setting mechanism for the computing device, said setting mechanism including a lever arranged to operate the guard, and a spring opposing the return of the lever to normal position and tending to retain the guard in active position. 85

10. The combination with a computing device and a master means for operating the same, said computing device and master means having relative lateral movement into and out of engagement, and a rotary guard movable into and out of position to obstruct 95 such relative lateral movement.

11. The combination with a computing device, of a register including a series of wheels, a shaft supporting said wheels, a guard carried by the shaft, a master wheel arranged to engage the wheels first named, and means for rotating the shaft to project the guard into interfering relation with the master wheel. 100

12. The combination with a computing device including a series of wheels, of a master wheel adapted to engage said wheels, and a guard located at the end of the series of wheels and movable into and out of position to prevent the engagement of said 105 wheels by the master wheel. 110

13. The combination with a computing device including a series of denominational wheels, of a rotary guard disk located at one end of the series of wheels and having a cut-away portion, and a master wheel laterally movable into engagement with the denominational wheels in one position of the disk and obstructed by said disk in another position thereof. 115

14. The combination with an adding mechanism including a series of denominational members, of a master actuator for said members, and guarding mechanism including a plurality of guarding devices 120 movable into position to prevent an operative engagement between the master means and the denominational members. 125

15. The combination with a computing mechanism including denominational mem- 130

bers and setting mechanism operative to set said members, of operating means for the computing device, and means preventing the operation of the computing device by the 5 operating means after the setting mechanism is moved and before said mechanism has completed its operative movement.

16. The combination with a computing device including denominational members 10 and setting mechanism operative to set said members, of operating mechanism for the computing device, and means controlling the effective engagement between the computing device and its operating mechanism, 15 said controlling means being co-actively related to the setting mechanism.

17. The combination with a computing

mechanism including elements which are moved out of normal position when the computing mechanism is operated, of setting mechanism operative to return said elements to normal position to permit another operation of the computing device, operating means for the computing device, and means preventing the operation of the 25 computing device by the operating means while said elements of the computing device are out of their normal operative positions.

In testimony whereof I affix my signature in presence of two witnesses.

REGINALD JAMES BRAY.
